HOOK TYPE SAWMILL LOG TURNER

Ivan L. Hale, Central Point, Oreg.

Application June 17, 1948, Serial No. 33,509

5 Claims. (Cl. 143—103)

1

This invention relates to log turners and is particularly adapted to the smaller type of sawmill.

In the operation of my new and improved log turner, the log can be pushed off the deck on to the head blocks of the carriage with a simple operation, and at the same time causing a minimum of damage to the lumber.

My log turner is so designed as to be able to pull the log from the head blocks on to the log deck and reposition the log on the head blocks against the knees after the same has been turned.

My log turner is admirably adapted to be operated by mechanical means.

The primary object of my invention is to provide a log turner for small mills, or in many cases larger mill operations, that will push the log from the deck on to the head blocks of the carriage requiring a minimum of power, due to the mechanical design of the turner.

Another object of my invention is the designing of a log turner that will not only push the log on to the carriage from the log deck, but by a simple control mechanism will convert the turner into a hook arrangement for turning the log back on to the log deck.

A still further object of my invention is the designing of a log turner that is completely surrounded within a master framework that can be installed with a minimum amount of effort, and that is rugged and rigid within itself.

Another object of my invention is to adapt a principle of mechanics requiring a minimum amount of power to exert the proper pressures for pushing the log on to the carriage from the log deck, and for turning the log from the carriage on to the said deck, all of this being done with a minimum of damage to the lumber.

And a still further object of my invention is the provision of a simple control mechanism for controlling the various operations of the turner by the operator.

These and other incidental objects will be apparent in the drawings, specification and claims.

Referring to the drawings:

Figure 1 is a plan view of my new and improved log turner mounted to a log deck adjacent the head blocks of a conventional carriage.

Figure 2 is a sectional view taken on line 2—2 of Figure 1 of the deck, carriage and my new and improved log turner mounted thereon.

Figure 3 is an enlarged sectional end view of the turner on line 3—3 of Figure 2 illustrating the method of mounting the same to the deck, and including the power means of operating the same.

2

Figure 4 is an enlarged detail sectional view taken on line 4—4 of Figure 2 illustrating part of the mechanism for controlling the various operations of the turner bar.

Figure 5 is an enlarged detail sectional side view of the roller supports for the turner bar, parts broken away showing the bar operating gear.

Referring more specifically to the drawings:

I have indicated a portion of a log deck consisting of the skids 1, supported on the conventional cross framework 2 and under piling 3. I have also shown a portion of a conventional type of carriage 4 with the usual head blocks 5 and the knees 6.

15 My invention consists of the log turner assembly, generally indicated by numeral 7, consisting of frame members 8 and 9 which are secured to the underside of the deck skids 1 by any suitable means, as by bolts 10. An operating shaft 11 is

20 journaled within bearings 12 associated with said frame members and is driven by any suitable source of controlled motor, as for instance the steam or air engine 13. I do not wish to be limited to any particular form of driving power as any approved power mechanism can be employed as long as the same can be operated in either direction.

25 Journaled to the shaft 11 is a guiding member 14 through which is slidably mounted a beam 15, which will be from here on called the turner bar.

The turner bar 15 has a rack 16 forming part thereof, which engages the spur gear 17, which in turn is keyed to the shaft 11 by the key 17A (Fig. 5). By rotating the spur gear in

30 either direction, the turner bar 15 will be moved through the guiding member 14 in the desired direction. The guiding member 14 may have rollers associated therewith for contacting the top of the log turner bar 15 if so desired, but in

35 my drawings I have merely illustrated the same as a plain guide member.

40 The weight of the log turner bar 15 is taken by the rollers 18 which are journaled freely to the shaft 11. This insures easy movement of the bar through the guide member 14 and a definite related clearance between the rack 16 and the spur gear 17.

45 Referring to Figure 2, I have illustrated three operations, first in full lines the inactive position of the turner, while in the dotted lines I illustrate the turner pulling the log from the head blocks 5 of the carriage on to the deck, and with the broken lines I illustrate the log being pushed back on to the head blocks 5 after

50 the same has been turned, or when a new log

is being pushed in to place. This is accomplished in the following manner.

A connecting rod or link 19 is pivotally mounted to the bar 15 at 20 at its one end, and is slidably mounted within the sleeve 21 at its opposite end. The sleeve 21 has stub shafts 22 forming part thereof. These stub shafts extend through the bearings 23 which form part of the frame members 8 and 9. One of these stub shafts is cored out at 24 and is adapted to receive the locking plunger 25 which in turn is operated by the lever 26 through the control rod 27, said control rod being operated either by foot pedal or lever action at the sawyer's station. The lever 26 is pivotally mounted to the bracket arm 28 and to the locking plunger 25, the object and purpose of this mechanism will be explained later on.

Referring to Figures 1 and 2, I will now describe the operation of my new and improved log turner. In the event it is desired to push a log from the deck on to the head blocks of the carriage, the shaft 11 is rotated by the power unit 13 so as to revolve the spur gear 17 in the direction of the arrow Fig. 5. This pushes the rod 19 through the sleeve 21 until the sawyer operates the control rod 27, lever 26 and the locking plunger 25 so as to force the end 25A of the plunger against the rod 19 within the sleeve 21, preventing its movement therethrough.

When this happens the rod 19 becomes dead ended forcing the turner bar 15 to the position illustrated by the broken lines against the side of the log 30, indicated by broken lines, and after the contact has been made with the log the sawyer releases his control permitting the rod 19 to slide within the sleeve 21, the bar 15 providing a straight push against the log. The bar can be retracted by the shaft 11 and the spur gear 17, causing the bar to travel in the opposite direction of the arrow in Figure 2 to the position illustrated in full lines, Figure 2. A cross member 31 prevents the end 32 of the bar from dropping down below that shown in full lines.

I will now describe the operation of turning the log after it has been on the carriage. The sawyer operates the control rod 27 and the locking plunger 25, after the motor 13 begins to move the log turner bar 15 in the direction of the arrow Fig. 2, causing the bar to assume the position indicated by the dotted lines extending clear over on to the carriage on top of the log. The dotted lines in Figure 2 show the same after it has grabbed the log and pulled it part way over. After the bar has contacted the top of the log the sawyer releases the locking plunger 25 permitting free movement of the rod 19, while the bar 15 is moved in the opposite direction and pulls the log over by reversing the direction of the shaft 11 by reversing the power unit 13. When the log is turned the above described operation takes place relative to the broken lines in pushing the same back on to the head blocks on to the carriage.

Located on top of the skids adjacent the carriage are plates 33 (referring to Figures 1 and 2). These plates are countersunk into the skidway as indicated at 35 and have a downwardly extending spindle 34, which is pivotally mounted within the skidway. The plates normally lie in the position illustrated in Figure 1, and it will be noted in Figure 2 that when the log is being turned, as indicated in the dotted position, the corner 36 of the log will strike against the edge of the plate holding the same while being rolled

onto the skids, and when the log reaches the broken line position the plate will hold the same slightly higher than the head blocks on the carriage, permitting the turner bar 15 to push the log over on to the head blocks.

In the event that it is desired to cut an extra heavy cant off the log, the plates 33 can be rotated to the dotted position illustrated in Figure 1, giving clearance for the cant to operate over the skids.

What I claim is:

1. A log turner, comprising in a frame, a power shaft mounted in the frame, a guide loosely mounted on the power shaft, a log turner bar mounted to reciprocate in the guide, a sleeve mounted in the frame, a link pivoted to the log turner bar at one end with its opposite end mounted to move in the sleeve, means for reciprocating the turner bar in the guide, and means for locking the sleeve and link together at different points in the length of the link to alter the movement of the free end of the turner bar when shifting a log.

2. A log turner as defined in claim 1, wherein the shaft is provided with a gear and the turner bar is provided with gear teeth which mesh with the gear.

3. A log turner as defined in claim 1, wherein the sleeve is provided with hollow trunnions, a rod mounted to move in a hollow trunnion, and means to move the rod to impinge the link at any point in its length.

4. In combination a saw carriage, a frame mounted adjacent to the saw carriage, a swinging and reciprocal log turner bar mounted in the frame, means mounted in the frame for swinging and reciprocating the log turner bar, said means including a pinion journaled in said frame and a rack on the under surface of said bar engaging said pinion, a guide member for said bar mounted on said frame, rollers journaled in said guide member on which the log turner bar is supported when reciprocating, and means pivotally connected at one end to the bar forwardly of the rack thereon and slidably connected at its opposite end to said frame for altering the inclination of the log turning bar to engage a log at different points and position.

5. The combination with a saw carriage and a frame mounted adjacent to the saw carriage, a log turner bar mounted to rock on a fulcrum and slide in the frame, means to limit the rocking of the bar, means for sliding the bar, anti-friction means between the bar and mount thereof, means operatively connected to the bar in front of the fulcrum thereof for altering the angular position of the bar on its fulcrum at different extended positions when slid in the frame, including a rod pivoted to the bar, means to slidably and pivotally support the opposite end of the rod, and means to hold the rod against sliding in its support to cause the bar to engage the log at different points.
